UNITED STATES PATENT OFFICE.

MARY A. LONG, OF AKRON, OHIO.

DESIGN FOR A WORK-STAND.

SPECIFICATION forming part of Design No. 25,484, dated May 12, 1896.

Application filed October 30, 1895. Serial No. 567,455. Term of patent 7 years.

To all whom it may concern:

Be it known that I, MARY A. LONG, a citizen of the United States, and a resident of Akron, in the county of Summit and State of Ohio, have invented and produced a certain new and original Design for a Work-Stand, of which the following is a specification, reference being had to the accompanying drawing.

10 The leading feature of my design consists in the work-stand herein shown.

The work table or stand for sewing is rectangular in outline, having supporting-legs provided with cross-bars at the base, as shown.

15 At the top is an open receptacle with closed

sides, end spindles, and supporting-cones at the top corners, with end drawers beneath the top, and extending side receptacles with covers.

A indicates the table-legs; A', the extending sides; B, the end drawer; C, the top lids; D, the cone; E, the end spindles; F, the base cross-bars.

What I claim is—

The design for a work-stand herein shown and described.

MARY A. LONG.
